UNITED STATES PATENT OFFICE.

SILAS JASPER SAXON AND WILLIAM HARTFORD JAMES, OF COLFAX,
WASHINGTON TERRITORY.

FENCE-POST.

SPECIFICATION forming part of Letters Patent No. 391,198, dated October 16, 1888.

Application filed June 14, 1888. Serial No. 277,042. (No model.)

To all whom it may concern.

Be it known that we, SILAS JASPER SAXON and WILLIAM HARTFORD JAMES, both of Colfax, in the county of Whitman and Territory 5 of Washington, have invented a new and Improved Fence-Post, of which the following is a specification, reference being had to the annexed drawings, forming a part thereof, in which—

10 Figure 1 is a side elevation of our improved fence-post. Fig. 2 is a vertical transverse section of the same. Fig. 3 is a horizontal section taken on line xx in Fig. 1. Fig. 4 is a horizontal section taken on line yy in Fig. 1, 15 and Fig. 5 is a horizontal section taken on line zz in Fig. 1.

Similar letters of reference indicate corresponding parts in all the views.

Our invention is an improvement in the class 20 of fence-posts having a metallic foot-piece which enters the ground, and is provided with a socket adapted to receive and support the body of the post.

Our invention consists, broadly stated, in the 25 means of connection between such foot-piece and the body of the post—that is to say, a thin metal tube is driven into the lower end of the wooden body of the post, and thus forms a light, cheap, but strong, firm, and durable attachment and extension of the same. This 30 tube fits somewhat loosely in the socket formed in the foot-piece, so that the body of the post may be easily and quickly attached to and detached from said foot-piece, as required in the 35 construction or repair or removal of the fence whereof such post forms a part.

Referring to the drawings, the lower portion of foot-piece A is shown provided with radial wings $a a'$, which are arranged at right angles

to each other and extend below the socket, forming anchor-plates for keeping the socket in a vertical position. The bore of the socket is preferably cylindrical, and the post B, which is supported by the socket, is provided with a tubular extension, b , which is driven into the lower 40 end of the post and projects beyond the end of the post sufficiently to give it a firm bearing in the socket A. The lower end of the post is provided with a ferrule, C, which is driven onto the lower end of the post to 45 strengthen it and prevent it from splitting.

The foot-piece A, with its wings $a a'$, is set in the ground in the same manner as an ordinary post, with the upper end of the socket even with the ground or a short distance above 50 the ground-level.

The foot-piece A is preferably made of cast-iron, and when set firmly in the ground requires no renewal or removal. The posts B may be removed from the sockets and replaced 55 whenever necessary.

Having thus described our invention, we claim as new and desire to secure by Letters Patent—

The combination, with the wood post B and 60 the foot-piece A, having a socket in its upper end, of the tubular metal connecting-piece b , which is inserted and held firmly in the end of the post and fits somewhat loosely in the 65 said socket, whereby the post is adapted to be 70 readily attached to and removed from the foot-piece, as specified.

SILAS JASPER SAXON.

WILLIAM HARTFORD JAMES.
